(57) **CLAIM**

The ornamental design for a display screen or portion thereof with graphical user interface, as shown and described.

DESCRIPTION

The FIGURE is a front view of a display screen or portion thereof with graphical user interface, showing my new design.

The outermost double broken-line rectangle illustrates a display screen or portion thereof and forms no part of the claimed design. The remaining broken lines in the figure depict portions of the graphical user interface that form no part of the claimed design.

1 Claim, 1 Drawing Sheet(56)
